(57) **CLAIM**

The ornamental design for road roller, as shown and described.

DESCRIPTION

FIG. 1 is a top front perspective view of the present road roller;

FIG. 2 is a top rear perspective view of same;

FIG. 3 is a front view of the present road roller;

FIG. 4 is a rear view of same;

FIG. 5 is a left side view of the present road roller;

FIG. 6 is a right side view of same;

FIG. 7 is a top view of the present road roller;

FIG. 8 is a top front perspective view of a second embodiment of the present road roller;

FIG. 9 is a top rear perspective view of the road roller of FIG. 8;

FIG. 10 is a front view of same;

FIG. 11 is a rear view of the road roller of FIG. 8;

FIG. 12 is a left side view of same;

FIG. 13 is a right side view of same; and,

FIG. 14 is a top view of same.

The structure shown in broken lines is for environment purposes only and does not form part of the claimed invention.
